Inventor:
Frank P. Whitaker,
by *Charles E. Tullar*
His Attorney.

UNITED STATES PATENT OFFICE

FRANK P. WHITAKER, OF RUGBY, ENGLAND, ASSIGNOR TO GENERAL ELECTRIC COMPANY, A CORPORATION OF NEW YORK

MERCURY ARC RECTIFIER

Application filed June 17, 1929, Serial No. 371,574, and in Great Britain June 20, 1928.

My invention relates to mercury arc rectifiers and the like and more particularly to apparatus for the prevention of arc-backs in such rectifiers.

5 The invention consists in surrounding each anode with an insulated anode shield, this shield being arranged to enclose the anode completely and to follow approximately the shape of the anode and be closely adjacent to it. In order to give access to the anode for the arc I may provide holes in the anode shield into which short lengths of tube may be fitted. In some cases it may also be advantageous for the other ends of the tubes 10 to be fitted into an open ended cylinder or the like.

A typical form of my invention is illustrated in the drawings in which Fig. 1 illustrates a vertical cross section of a shield constructed according to my invention and Fig. 20 2 illustrates a horizontal cross section taken on line 2—2 of Fig. 1.

In Fig. 1, 10 is the anode which is introduced through the wall of the vacuum chamber of the rectifier by means of an insulator 25 11. The cylindrical anode shield 12 may be carried on this insulator and surrounds the anode closely and completely. Opposite the working face of the anode, holes 14 are provided in the anode shield to give the arc access to the anode and into these holes short lengths of tube 15 are fitted. The bottom ends of the tubes 15 may be fitted into corresponding holes in the closed upper end of 30 cylinder 16, the lower end of which is open.

The best proportions for the arrangement are found by experiment in individual cases, but generally the distance from the anode surface to the anode shield is of the order 35 of magnitude of an inch. The tubes 15 will also be about an inch in diameter.

In certain cases it may be advantageous to taper the tubes 15 or the cylinder 16. In other cases the cylinder 16 may be completely 40 omitted.

What I claim as new and desire to secure by Letters Patent of the United States, is,—

1. In a vapor discharge device, an anode, an insulated shield arranged to surround 45 said anode and provided with a perforated

wall arranged below said anode, the diameter of said perforations being substantially one inch.

2. In a vapor discharge device, an anode, a cylindrical shield arranged to surround said anode and provided with a perforated wall arranged below said anode and spaced from said anode a distance of substantially one inch, and a plurality of tubes extending through said perforations. 55

3. In a vapor discharge device, an anode, a cylindrical shield arranged to surround said anode and provided with a perforated wall arranged below said anode, and a plurality of tubes inserted in the perforations of said wall, the distance between said wall and said anode being substantially equal to the diameter of said tubes. 65

4. In a vapor discharge device, an anode, an insulated shield arranged to surround said anode and provided with a perforated wall arranged below said anode, a second shield similar to said first shield and arranged to have its perforations opposed to the perforations of said first shield, and tubes arranged 70 75 to extend between said opposed perforations.

In witness whereof, I have hereunto set my hand this 27th day of May, 1929.

FRANK P. WHITAKER.
